UNITED STATES PATENT OFFICE.

LOUIS LOWY, OF NEW YORK, N. Y., ASSIGNOR OF ONE-HALF TO ISIDORE GROSSGOLD.

AUTOMATIC PLASTER-SUPPLYING DEVICE.

Application filed September 3, 1927. Serial No. 217,841.

This invention relates to a new and useful device in the nature of an automatic plaster supply device provided for the purpose of supplying plaster through a hollow flexible member as a means of eliminating the manual effort ordinarily required to transport or carry plaster, such as is used to plaster walls, ceilings, and the like, of buildings, to the wall where same is to be used or applied.

10 The object of the invention is to provide a device of the class described of novel construction and arrangement of parts herein-after more fully described, claimed, and illustrated in the accompanying drawing.

15 Fig. 1 is a side elevational view of my improved device as same would appear when in use.

20 Fig. 2 is a central longitudinal sectional view thereof illustrating a further development of my improved device.

25 Fig. 3 is a fragmentary sectional view taken on the line 3—3 of Fig. 2.

Fig. 4 is a fragmentary perspective view thereof, illustrating in particular another development of my improved device.

30 Fig. 5 is a fragmentary sectional view illustrating in particular the hopper as embodied in my improved device.

Fig. 6 is an enlarged sectional view taken on the line 6—6 of Fig. 2.

35 As here embodied my improved automatic plaster supply device comprises the usual screw conveyor 10 mounted on the shaft 11 rotatively mounted in the front and rear end plates 12 and 13 of the tubular member 14. The tubular member 14 is of suitable diameter to closely conform to the outer diameter or periphery of the screw conveyor 10.

40 The tubular member 14 is provided with downwardly extended elements 16 or feet secured as at 17 by bolts, screws, studs, or the like, to the base plate 18.

45 The front end plate 12 is provided with an extended portion 19 of tubular construction over which one extremity of the flexible hollow member 20 is slidably engaged, and which is secured thereto as at 21 by the usual clamp as a means of securely holding the said flexible member 20 in place. Similar flexible hollow members 21' are secured by the ordinary couplings 22' to each other and to the first mentioned flexible hollow member 20, so as to provide a continuous flexible hollow line of any desired length. The valve 22 is

55 attached to the free extremity of the flexible members 21' and is provided with a nozzle element 23 extended therefrom.

The worm 24 is mounted on the rear extended extremity of the shaft 11 and meshes with the worm gear 25 rotatively mounted on 60 the pin 26 carried in the bracket 27 secured to the base plate 18.

65 The shaft 28 is rotatively mounted in the housing 29 and in the bracket 30 secured to the said housing. The clutch member 30' is secured to the inner extremity of the shaft 28 and is provided with radial recesses 31. The shaft 28 is extended outwardly from the housing 29 and has mounted on its extended extremity a worm 32, meshing with the above 70 mentioned worm gear 25. The shaft 33 is mounted in the housing 29 and in the bracket 34 secured to the said housing and is in alignment with the said shaft 28. The inner extremity of the shaft 33 has formed therein 75 longitudinal recesses 35 or serrations, adapted to slidably receive the clutch member 36 as a means of driving the said clutch member 36 when the shaft 33 is rotated or driven, as hereinafter set forth. The clutch member 36 is provided with radial teeth 37 adapted to slidably engage in the above mentioned radial recesses 31 formed in the first mentioned

80 clutch member 30' as a means of rotating or driving the shaft 28. The shaft 38 is rotatively mounted in the housing 29 and is provided with a forked element 39 adapted to engage the clutch member 36. The lever 41 is secured to the outer extended extremity of the shaft 38 and is provided with a handle element 42. The housing 29 is of box like construction of suitable size to enclose the above mentioned mechanism and is provided with a cover member 42'.

85 The said housing 29 is mounted on the base plate 18. The pulley 43 is mounted on the outer extended extremity of the shaft 33, adapted to receive a bolt extended over the pulley 43 and a similar pulley mounted in any suitable convenient prime mover, as a means of driving my improved device. The latter mentioned elements are not shown in the accompanying drawing.

90 It should be understood that a suitable electric motor 44 may be mounted on the base plate 18 and operatively attached to 95 the shaft 33 as a means of driving my improved device. The said electric motor 44 is connected by means of the electric wires 46 to 100 105

any suitable convenient source of electric current.

The hopper 51 of hollow cylindrical construction is secured at its lower extremity to the above mentioned tubular member 14 and extended vertically upwardly therefrom. The bevel pinion 52 is mounted on the outer extended portion of the said shaft 11 and meshes with a similar bevel pinion 53, mounted on the shaft 54 rotatively mounted in the brackets 55 and 56 secured to the hopper 51. The bevel pinion 57 is mounted on the upper extremity of the shaft 54 and meshes with a similar bevel pinion 58 secured to the shaft 59 rotatively mounted in the extended element 60 of the said bracket 56. The shaft 59 is provided with an enlarged portion 61 or collar element adapted to retain the pinion 62 in position on the said shaft. The pinion 62 is keyed to shaft 59. The pinion 62 is removably secured to the shaft 59 by means of the collar 64 slidably engaging over the said shaft and the usual drift key 65 somewhat tapered and adapted to removably engage in a similar tapered opening formed in the said shaft 59 at or near the extremity thereof. The piston 66 slidably engages in the hopper 51 and has secured thereto and extended upwardly therefrom a rod 67 having formed therein rack teeth 68 adapted to engage the teeth of the pinion 62. The above described construction is such as will permit the plaster placed in the hopper 51 to be forced under pressure into the tubular member 14 by the downward movement of the piston 66 which is actuated by the movement or rotating of the shaft 11. It should be understood that when the said piston 66 has reached the downward position thereof as designated by the reference numeral 69 that the pinion 62 is removed from the shaft 59 and the piston 66 readily and easily removed from the hopper 51 so as to permit the hopper 51 to be refilled.

I have also shown a workman provided with the above mentioned nozzle 23 as a means of filling the container 71 or what is usually known as the "hod" in proximity to the wall 72 to be plastered.

In Fig. 2 of the accompanying drawing, I have shown a container 72' of box-like construction, mounted on the supports 73, secured to the tubular member 14. The cover 74 is slidably mounted in the container 72' and is normally forced downwardly by the expansion spring 75 positioned intermediate the cover 74 and the brace member 76, hinged as at 77, to the container 72' and held in a closed position by means of the wing nut 78 threadedly mounted on the screw 79, hinged, as at 79', to the container 72'. The flexible hollow member 80 is secured at one extremity to the bottom portion of the container 72' and to the flanged portion 81 of the hopper 51, adjacent to the lower portion thereof.

The flapper valve 82 indicated open by dot dash lines 82', is hinged, as at 83, to the inner lower portion of the hopper 51, and is adapted to enclose or cover the opening formed in the hopper 51 at the flanged portion 81 thereof. The above described construction is such as will permit the plaster 84 placed in the container 72' to be forced downwardly by the spring 75, and by the suction of the piston 66, on the up or return stroke of the said piston, as a means of filling the hopper 51. It should be understood that the flapper valve 82 will be forced open, as designated by the reference numeral 82' during the return stroke of the piston 66, so as to permit the said plaster 84 to enter the hopper 51, and that the downward stroke of the piston 66 will close the flapper valve 82, so as to permit the plaster drawn into the hopper 51 to be forced into the tubular member 14. The pinion 85 is freely mounted on the shaft 59, and held thereon by the collar 86 secured to the shaft 59. The ratchet pawl 87 is pivotally secured to the pinion 85, and is normally held in engagement with the ratchet indentations 89 formed in the shaft 59 adjacent to the pinion 85 by means of the tension spring 90 secured to the ratchet pawl 87, and to the pinion 85. The above described construction is such as will permit the shaft 59 when rotated as above set forth to drive or rotate the pinion 85 in one direction only, so as to force the piston 66, downwardly into the hopper 51.

I have also provided a solenoid, having a fixed field 91, and having the wires 92 and 93, thereof, suitably connected to any convenient source of electric current. The field 91 of the solenoid is mounted on the support 94, secured to and extended upwardly from the hopper 51. The movable core of the said solenoid is connected to the free extremity of the rod 67. The above described construction is such as will force the piston 66, upwardly, on its return stroke, when the field 91 of the said solenoid is energized.

I have also provided a tubular member 96 secured to the bottom of the tubular member 14, directly below the hopper 51. The plate 97 is slidably mounted in the tubular member 96, and is normally held in an upper position, against the lug elements 98, by means of the expansion spring 99, positioned in the tubular member 96 intermediate the plate 97 and the base 100. The base 100 is threadedly secured to the lower inner extremity of the tubular member 96 and is provided with lug elements 101, as a means of rotating the base 100, so as to increase or decrease the effective pressure of the spring 99. The above described construction is such as will permit plate 97 to function as a relief valve as a means of preventing the flexible hollow members 20 and 20' from being broken due to the pressure exerted by the piston 66 in event the nozzle 23 is closed. It should be under-

stood that the action of the said relief valve may be adjusted by the adjustment of the base 100.

In Fig. 4 of the accompanying drawing I 5 have shown the above mentioned front end plate 12 provided with a plurality of extended portions 19 adapted to receive a plurality of hollow flexible members 20 as a means of permitting the plaster to be simultaneously 10 forced to a number of desired places as would be desirable when plastering a number of rooms in a building.

In Fig. 1 of the accompanying drawing, I 15 have shown a flexible hollow member 48 secured at one extremity to the water faucet 49. The flexible member 48 is provided with a nozzle 50 secured to the free extremity thereof. The above described construction is such as will permit water to be forced into my 20 improved device, through the hopper 51 as a means of flushing out the interior thereof, and the flexible hollow members 20 and 20' as a means of preventing clogging. I have also provided a rod 102, normally removably 25 secured to the base plate 18, by means of the clips 103, attached thereto. The rod 102 is provided with a handle element 104, as a means of manipulating the said rod. The above described construction is such as will 30 permit the rod 102 to be used to clean the flexible hollow members 20 and 20' when the said flexible hollow members are disconnected by means of the couplings 22'.

Having thus described my invention what 35 I claim as new and desire to protect by Letters Patent of the United States is as follows:

1. In a device of the class described, a tubular member provided with a screw conveyor, a hopper connected with the tubular member, a piston slidably engaged in the said hopper, a means for mechanically forcing the piston downwards, a solenoid connected for 40 returning the piston, a container connected to the hopper, a flapper valve connected to the 45 hopper so as to be capable of closing the connection between the container and hopper,

and a means for forcing plastic material from the container towards the hopper, so that as the piston travels upwards, the plastic material 50 enters the hopper.

2. In a device of the class described, a tubular member provided with a screw conveyor, a hopper connected with the tubular member, a piston slidably engaged in the said hopper, a means for mechanically forcing the piston downwards, a solenoid connected for 55 returning the piston, a container connected to the hopper, a flapper valve connected to the hopper so as to be capable of closing the connection between the container and hopper, and a means for forcing plastic material from the container towards the hopper, so that as the piston travels upwards, the plastic material 60 enters the hopper, the latter means consisting of a cover slidably arranged in the container, a brace member attached to the container, and an expansion spring acting between the cover and brace member.

3. In a device of the class described, a tubular member provided with a screw conveyor, a hopper connected with the tubular member, a piston slidably engaged in the said hopper, a means for mechanically forcing the piston downwards, a solenoid connected for 65 returning the piston, a container connected to the hopper, a flapper valve connected to the hopper so as to be capable of closing the connection between the container and hopper, a relief valve connected with the tubular 70 member, and being capable of relieving pressure caused by the downward movement of the piston, and a means for forcing plaster material from the container towards the hopper, so that as the piston travels upwards, the plastic material 75 enters the hopper.

In testimony whereof I have affixed my signature.

LOUIS LOWY.
